UNITED STATES PATENT OFFICE

JORDAN W. GRANT, OF PORTSMOUTH, VIRGINIA

NOZZLE

Application filed April 8, 1930. Serial No. 441,295.

This invention aims to provide a nozzle stand so constructed that a stream of water may be directed in any desired direction, with regard to the vertical, it being possible, also, to dispose the stream of water in any desired position around a circumference having a vertical axis. The invention aims to stabilize and strengthen the mechanism and to improve generally and to enhance the utility of devices of that type to which the present invention appertains, other and further objects being explained as the description proceeds.

With the above and other objects in view, which will appear as the description proceeds, the invention resides in the combination and arrangement of parts and in the details of construction hereinafter described and claimed, it being understood that changes may be made in the precise embodiment of the invention herein disclosed, within the scope of what is claimed, without departing from the spirit of the invention.

In the accompanying drawings:—

Figure 1 shows in vertical longitudinal section, a device constructed in accordance with the invention;

Figure 2 is a section taken through the nozzle and attendant parts;

Figure 3 is a top plan, with parts in section;

Figure 4 is a section on the line 4—4 of Figure 1;

Figures 5 and 6 are elevations showing the nozzle turned to different positions.

The device forming the subject matter of this application preferably is made of metal, and includes a body 1 provided near to its upper end with an outstanding flange 2. A base plate 3 is attached by securing elements 4 to the bottom of the body. The base plate 3 carries brackets 5 which abut at their inner ends against the body 1, the brackets 5 engaging beneath the flange 2, as clearly shown in Figure 1 of the drawings. In the brackets 5 are mounted vertically adjustable feet 6 which may be screws. The base plate 3 is provided with holes 7, so that the device can be bolted down, if desired, the feet 6 cooper-

ating with the platform or other support (not shown) on which the device is mounted.

The body 1 includes a hollow extension 8 having laterally projecting brackets 9 in which are mounted vertically adjustable feet 10, preferably screws.

Valve seats 11 are threaded into the outer end of the extension 8 of the body 1. Sleeves 12 are threaded into the outer ends of the valve seats 11. Hose couplings 14 are mounted to rotate on the outer ends of the sleeves 12. Packings 15 are located within the couplings 14, in engagement with the outer ends of the sleeves 12. Washers 16 may be located between the hose couplings 14 on the one hand, and the valve seats 11 and the end of the extension 8 on the other hand. In general, however, the hose couplings 14 may be mounted in any desired way on the part 8 of the body 1.

The end of the extension 8 of the body 1 has inwardly projecting partitions 17 disposed between inlets represented by the hose couplings 14. Pivot elements 18 are mounted on bosses 19 carried by the top and the bottom of the extension 8, as shown in Figure 1. Valves 20 cooperate with the valve seats 11 and are mounted to swing on the pivot elements 18. Springs 21 are engaged around the pivot elements 18. The springs 21 are engaged at one end with the valves 20 and at the other end with the partitions 17. The function of the springs 21 is to hold the valves 20 normally engaged with the seat 11. The body 1 has an upstanding tubular neck 22.

The numeral 23 marks a hollow head having a bottom 24. The bottom 24 of the head 23 rests on the top of the body 1 and is located about the neck 22, as Figure 1 will show. A ring 25 is held by securing elements 26 on the bottom 24 of the head 23, and holds a packing 27 in place about the neck 22, to avoid leakage.

The top of the head 23 carries a cup-shaped housing 28 within which is located a ball bearing 29. The lower end of a shaft 30 is threaded at 34 into the bottom of the body 1. The upper end of the shaft 30 is 100

threaded into the upper end of the ball bearing 29, and the upper end of the shaft 30 may be held to the upper end of the ball bearing by means of a pin 31. The shaft 30 constitutes a retainer which holds the hollow head 23 on the body 1 for rotation. The ball bearing 29 is protected by a cover 32 which is threaded on the outer end of the housing 28. In the top of the cover 32, a 10 stub shaft 33 is mounted for rotation, the shaft 33 being provided at its inner end with a disc like foot 34 which is rotatably mounted in a recess 35 formed in the under surface of the cover 32. The cover 32 exercises a 15 double function, in that it protects the ball bearing 29, and also holds the stub shaft in place for rotation.

The numeral 36 marks a curved brace rod which is pivotally connected at 37 at its inner end with the outer end of the stub shaft 33. The head 23 has a lateral projection 43 provided with a recess 39 (Figure 1) in which slides a brake 38, adapted to cooperate with the top of the body 1. The brake 38 has a reduced stem 40 supplied with a turning head 41 external to the member 23. A compression spring 42 is interposed between the turning head 41 and the end of the projection 43. The stem 40 is threaded 30 into the projection 43.

The hollow head 23 has a tubular transverse portion 45 (Figure 4). The numeral 49 marks an outlet pipe having diverging arms 48 provided with inwardly extended 35 ends 47 held by couplings 46 on the part 45 of the casing 43, the construction being such that the outlet pipe 49 can swing with the axis of the part 45 as a center of swinging movement. A valve casing 50 is threaded 40 on the outlet pipe 49, and a nozzle 51 is threaded or mounted otherwise on the valve casing 50. In the valve casing 50, a valve 52 is rotatably mounted, and controls the flow through the nozzle 51. The valve 52 has a 45 large gear 53 meshing with a smaller pinion 54 on a shaft 55 journaled in the valve casing 50, the shaft 55 being provided with a handle 65 of any desired kind, whereby rotation can be imparted conveniently to the shaft.

50 The outlet pipe 49 has outstanding ears 56 in which a bearing 57 is mounted to turn. A latch 58 is slidable in the bearing 57 and presses against the brace or radius rod 36, the radius rod 36 having a seat 63 with which the 55 latch 58 cooperates. The latch 58 has a stem 59 slidable in a cap 60 on one end of the bearing 57. The stem 59 of the latch 58 has a finger piece 62. A compression spring 61 is located within the bearing 57 and within the 60 cap 60 and thrusts the latch 58 against the radius rod 56. The latch 58, thus, acts as a friction grip. A set screw or clamping device 64 is threaded in the bearing 57 and is 65 adapted to engage the radius rod 56 at the will of an operator.

In practical operation, the water enters by one or more of the couplings 14 and flows into the body 1, the valves 20 opening to admit the water. When any hose is disconnected at any one of the couplings 14, the corresponding valve 20 closes automatically under the action of the spring 21. The partitions 17 serve to prevent the water from swirling about, as it enters the body 1. The water flows from the body 1 into the head 23. The head 23 can be turned on an axis represented by the shaft 30 in Figure 1. From the head 23 the water flows by way of the arms 48 into the outlet pipe 49. The outlet pipe 49 can swing on an axis represented by the axis of the part 45 in Figure 4, and, thus, the nozzle 51 has practically a universal movement, since the nozzle can be swung upwardly and downwardly, and be swung around horizontally, as well.

70 The brake 38 of Figure 1 may be set down on the body 1 to hold the head 23 in any position to which it has been rotated, the brake 38 being advanced and set by turning down the threaded stem 40 through the instrumentality of the head 41.

75 The nozzle 51 can be swung upwardly and downwardly, and the spring 61 of Figure 2 will cause the friction grip 58 to engage the radius rod 36 and hold the nozzle 51 in any 80 position to which it has been adjusted, vertically. When the nozzle is swung down far enough, the member 58 will engage in the seat 63, the part 58 then acting as a latch to limit further downward swinging of the nozzle. The operator, however, can pull back the latch 58, by means of the finger piece 62, and let the nozzle 51 swing downwardly further than would be the case if the latch 58 were engaged in the seat 63. If the operator wishes 85 the nozzle to be held with a firmer hold than is provided through the instrumentality of the latch 58, then the set screw or clamp 64 of Figure 2 can be advanced to bind tightly on the radius rod 36.

90 Especial attention is given to the fact that the body 1, considered as to vertical section, is wedge-shaped as shown in Figure 1, the hose couplings or inlets 14 being at the wider end of the wedge, and the outlet, represented by the member 45, being above the narrow end of the wedge. This construction gives a 95 good width at one side of the device to accommodate hose couplings 14 of large diameter, and, at the same time, brings the outlet, represented by the part 45, down close to the ground, thereby giving the device stability.

100 Each of the inlets has its individual valve 20, and the partitions 17 not only prevent swirling, but, also, serve as internal reinforcements for the body 1. The body, therefore, is well adapted to withstand extreme pressures, and water hammer. The several brackets 5 and 9, together with the parts associated therewith, afford stability, both as 105 110 115 120 125 130

to the mounting of the device and as to its capacity for resisting pressure strains and other strains. The shaft 30 is useful not only as a means for holding the head 23 on the body 1, but also is useful as a reinforcing means. The parts 47, 48, and 49 are so constructed that the water can pass through them with a minimum amount of friction, and the same observation holds true with respect to other parts through which the water passes. The radius rod or brace 36 cooperates automatically with the member 58 of Figure 2 to hold the nozzle 51 in any position to which it may be swung vertically, and, as has been stated hereinbefore, a positive holding may be brought about by advancing the clamp screw 64. It will be observed that the nozzle 51 may be swung over from the position of Figure 6 to the position of Figure 5, thereby conferring a large degree of adjustability upon the device. The water entering by way of the hose couplings 14 proceeds along straight lines to the center of the body 1, an arrangement, which, obviously is of great utility in a device of the class described.

Having thus described the invention, what is claimed is:

1. In a device of the class described, a hollow body having an inlet, a head, means for journaling the head on the top of the body for rotation about an upright axis, means for holding the head on the body for rotation as aforesaid, a nozzle carrier mounted to swing vertically on the head, a radius rod, means for mounting the radius rod pivotally and rotatably at its lower end on the top of the head, at a point near to the center of the head, and a holding mechanism on the nozzle carrier, wherewith the radius rod is slidably engaged, the rod having a free end extended upwardly along the nozzle carrier and lying alongside the nozzle carrier when the nozzle carrier is in a substantially vertical position, thereby preventing the radius rod from projecting laterally beyond the body when the nozzle carrier does not also project laterally beyond the body, the radius rod being adapted to support the nozzle carrier at various inclinations.

2. A device of the class described, constructed as set forth in claim 1, and further characterized by the fact that the holding mechanism embodies a bearing in which the radius rod slides, means for mounting the bearing for rotation on the nozzle carrier, a spring-pressed member mounted in the bearing and engaging the radius rod, and a clamping device carried by the bearing and engaging the radius rod at the will of an operator.

3. In a device of the class described, a hollow body having a plurality of inlets, partitions in the body, between the inlets, and extended inwardly far enough to form chambers of appreciable size about the inlets, a

head journaled on the top of the body for rotation about an upright axis, a nozzle carrier mounted to swing vertically on the head, an outwardly closing automatic check valve at the inner end of each of the inlets, the valves being housed in the body, between the partitions, and spring means for closing each valve when there is no hose on the corresponding inlet, and when the back pressure, incident to the use of such a hose, is removed, and spring means for closing each of the valves, the said spring means being engaged with the partitions.

In testimony that I claim the foregoing as my own I have hereto affixed my signature.
